UNITED STATES PATENT OFFICE.

GEORGE W. SMITH, OF DAYTON, OHIO, ASSIGNOR TO OHMER FARE REGISTER COMPANY, OF DAYTON, OHIO, A CORPORATION OF NEW YORK.

DIE-CASTING MACHINE.

Application filed June 16, 1921. Serial No. 478,152.

To all whom it may concern:

Be it known that I, GEORGE W. SMITH, a citizen of the United States, residing at Dayton, in the county of Montgomery and State of Ohio, have invented certain new and useful Improvements in Die-Casting Machines, of which the following is a specification, reference being had therein to the accompanying drawing.

10 This invention relates to a die casting machine.

One object of the invention is to provide a die casting machine which can be manipulated by a single operator to produce 15 castings at a high rate of speed.

A further object of the invention is to provide a machine of this kind of such a character that air will be prevented from entering the dies along with the metal, 20 thereby reducing to a minimum the number of defective castings due to blow holes.

A further object of the invention is to provide a machine of this kind in which the finished casting will be automatically 25 released and ejected.

A further object of the invention is to provide a machine of such a character that little or no adjustment will be necessary to accommodate the same to dies of different 30 kinds and sizes.

Other objects of the invention will appear as the device is described in detail.

In the accompanying drawings Fig. 1 is a side elevation of a machine embodying my invention, partly in section; Fig. 2 is 35 a plan view of the same, partly in section; Fig. 3 is an end elevation of the machine; Fig. 4 is a section taken on the line 4—4 of Fig. 1, looking in the direction of the arrows; Fig. 5 is a transverse sectional view 40 taken on the line 5—5 of Fig. 1, looking in the direction of the arrows; Fig. 6 is a transverse sectional view of the controlling valve; Fig. 7 is a longitudinal section 45 view of the controlling valve; Fig. 8 is a detail view of the disk forming part of the valve; Fig. 9 is a sectional view of a melting pot; and Fig. 10 is a detail view, partly in section, showing the controlling 50 device for the valve of the melting pot.

In these drawings I have illustrated one embodiment of my invention and it will be

understood that this particular embodiment has been chosen for the purpose of illustration only and that the mechanism may 55 take various forms without departing from the spirit of the invention.

In that form of the invention here illustrated the machine comprises a main frame consisting of a base 1 having upright frame 60 members 2 and 3 arranged near the ends thereof and connected one to the other by tie rods 4 extending lengthwise of the machine and arranged parallel one to the other. Mounted on the frame are two die supporting members, or plates, 5 and 6, which are movable toward and from the end plate 2 of the main frame and which are also movable relatively one to the other. These plates are adapted to have secured to their 65 inner faces the die blocks 7 and 8 within which the casting is formed. When the die supporting member 5 is in its foremost position, that is, its position nearest the frame member 2, the die block carried thereby is 70 placed in communication with the discharge opening of the melting pot and when the die supporting member 6 is moved forwardly to the limit of its movement the faces of the two die blocks will be brought into 75 contact and the die closed preparatory to the making of the casting. The die supporting members may be mounted on the frame in any suitable manner, but in order that the die blocks may be retained in true 80 parallelism and to facilitate the movement of the die supporting members I prefer to mount these members upon the tie rods 4, the tie rods constituting guideways upon 85 which the two members have sliding movement. As here shown, the forward die supporting member 5 is rigidly secured at its corners to four sleeves 9 which fit snugly upon and are slidable upon the respective rods 4, thus providing long bearings for 90 the die supporting member and retaining the same at all times at right angles to the guide rods and parallel with the frame member 2, and thus causing the same to move in a right line toward and from the frame member. The rear die supporting member 6 is also secured at its corners to sleeves, or elongated bearings, 10 which are 95 preferably mounted upon the sleeves 9 of 100

the forward die supporting members. The sleeves 10 also fit snugly upon, but have sliding movement upon the sleeves 9 so that the two die supporting members, or plates, 5 are retained at all times in true parallelism. Movement may be imparted to the die supporting members 5 and 6 in any suitable manner but I prefer to employ power operated mechanism for actuating these members and, as here shown, I have utilized hydraulic power for this purpose. By employing a fluid operated actuating device for the die supporting members I am enabled to use dies of various sizes and kinds with little or no adjustment of the mechanism to accommodate the same thereto, because the fluid operated device will actuate the die supporting members until they reach their final positions and will then maintain a steady pressure thereon in any position in which they may be stopped, and, consequently, will operate in the same manner and as efficiently with very thick die blocks as it will with relatively thin die blocks. The pressure of the fluid is transmitted to the die supporting members in such a manner that the movement thereof may be interrupted at any point without disarranging the mechanism or interfering with the cycle of operations of the mechanism as a whole. A hydraulic mechanism is preferable for this purpose because it is more easily controlled than air or the like, as oils and similar liquids are practically noncompressible and therefore have no tendency to expand after the pressure has been cut off. The hydraulic mechanism may be of any suitable character and may be connected with the die supporting members in any suitable manner. In the present construction I have shown a hydraulic cylinder 11 mounted in a horizontal position on the end frame member 3, in line with the die supporting members. A piston 12 is mounted in this cylinder and has connected therewith a piston rod 13 extending forwardly therefrom and connected with a cross head or spider 14, the arms of which are rigidly secured to the rear ends of the sleeves 10 of the rear die supporting member 6. It will be apparent, therefore, that when fluid under pressure is admitted in the rear of the piston 12 the cross heads will be moved forwardly thus carrying the rear member 6 forwardly until the die block thereon engages the die block on the forward member 5 and the two members will then be carried forwardly together until the forward member reaches the forward limit of its movement, in which position, as has been stated, the dies are in communication with the melting pot. To retract the die supporting members fluid is admitted in front of the piston and the rear die member is retracted until its sleeves come in contact with collars 15 secured to the sleeves 9 of the forward die supporting member 5. It is desirable, however, that the forward member be retracted simultaneously with the rear member and I have, therefore, provided separate means for retracting this forward member. In the present instance this means consists of two weights 16 which are connected by cables 17, extending about guide pulleys 18, with the collars 15 on the sleeves 9 of the forward die supporting member. Consequently, as soon as the pressure on the piston is relieved the forward die supporting member will be retracted until the ends of its sleeves engage stops, or collars, 19 on the guides rods 4, and the rear member will be retracted until its sleeves have engaged the stops, or collars, 15, thus separating the two die supporting members and moving the forward die supporting member away from the frame member 2. The operation of the fluid operated device may be controlled in any suitable manner and, as here shown, pipes 20 and 21 lead respectively from the front and rear ends of the cylinder 11 to a valve 22 which is arranged in such a position that it may be conveniently manipulated by the operator from his station at the side of the machine and this valve member in turn is connected with the pressure line 23 leading to a source of supply for oil, or other fluid under pressure, and with an exhaust or discharge line 24. The valve preferably is of such a character that the supply, or pressure, pipe 23 may be connected with either end of the cylinder, or cut-off, from both ends of the cylinder, and the particular form of valve here shown comprises a valve casing consisting of a cup shaped portion 25 forming an inlet chamber and connected with the supply pipe 23. Connected with and preferably screw threaded into the cup shaped member 25 is a second member, or block, 26, having formed therein longitudinally extending ports, or chambers, 27 and 27^a opening through the inner end of the member 26 and communicating respectively with the pipes 21 and 20 leading to the cylinder 11. The member 26 of the casing also has formed therein a chamber which is connected with the exhaust pipe 24 and which is provided with a port 28. Mounted within the concave member 25 and bearing against the end of the block 26 is a disk-like valve member 29 which is rigidly secured to and rotatable with a valve rod, or a shaft, 30 mounted at its outer end in a bracket 31 and having secured thereto a handle 32 by means of which it and the connected valve member, may be rotated. A spring 33 presses against the disk-like valve member and holds the same firmly seated against the end of the part 26 of the valve casing. This valve member has

formed therein ports 34 and 35 which open through the same, and is also provided in its inner face with an elongated port or groove 36 which extends part way through the disk and which is here shown as arranged between the ports 34 and 35. When the valve is in its intermediate, or neutral, position, as shown in Figs. 6 and 8, the ports 34 and 35 of the valve member 29 are out of line with the respective ports 27 and 27^a and the elongated port 36 is in line with the exhaust port 28 but is out of line with the ports 27 and 27^a, and both the inlet ports and the exhaust ports are closed. If the valve member is rotated clock wise, in Fig. 6, which will be counter clock wise in Fig. 1, the port 34 will be brought into line with the port 27 and the elongated port 36 will be moved into line with the port 27^a but will remain in line with the port 28, thus permitting the fluid to pass from the supply pipe through the valve chamber, ports 34 and 27, and pipe 21 to the rear end of the cylinder and in permitting the fluid to pass from the other end of the cylinder through the pipe 20 through the ports 27^a, 36, and 28 to the exhaust pipe 24. By moving the valve in a counter clock wise direction, in Fig. 6, to the position shown in Fig. 1, the port 35 will be brought into line with the port 27^a and the port 36 will be brought into line with the port 27, whereby the connections are reversed and the supply pipe 23 is connected with the supply pipe 20 leading to the forward end of the cylinder and the pipe 21 is connected with the exhaust pipe. The valve disk 29 is preferably provided with a slot 129 into which extends a fixed pin 130 which serves to limit the movement of the valve member in both directions.

The major portion of the casting is usually formed in the rear die block 8 and to eject the casting from the die block I have slidably mounted in the die supporting member 6 a series of fingers, or pins, 37 which extend through the die block and engage the casting therein. These pins are connected at their outer ends by a plate 38 arranged in the path of a larger plate 39, slidably mounted on studs 40 projecting radially from the member 6 and acted upon by springs 41 which tend to move the same away from the member 6. Rods 42 mounted in the rear frame member 3 project forwardly and lie in the path of the plate 39 so that as the die supporting member 6 approaches the rear limit of its movement the plate 39 will be engaged by the rods 42, forced forwardly against the plate 38 which carries the pins 37, thereby actuating the pins and causing the same to release the casting from the die. In the present machine I have also provided means for cutting the gate away from the casting and ejecting the same from the die and from the tapered opening 43 in the forward die supporting member 5, which serves to connect the die with the melting pot. The die here shown is for casting a type wheel, such as are used on registers and computing machines of various kinds, and inasmuch as such a wheel is cast with a central opening to receive the shaft which is to carry the same I have utilized the cutting device as a core for forming this central opening in the type wheel. As here shown, a rod 44 is slidably mounted in the rear die supporting member 6 and extends forwardly through the die block so that it projects into the opening in the die for a distance slightly less than the depth of that opening, thereby avoiding closing the opening or interfering with the entrance of the molten metal. At the proper time, after the metal has been admitted to the die and before the pressure on the metal has been relieved, the rod 44 is forced forwardly, thus cutting away the gate and permitting the casting to move rearwardly with the die block. After the die blocks have been moved rearwardly a further forward movement is imparted to the rod 44, causing the same to engage the gate and force the same from the opening 43, this latter operation taking place after the forward die supporting member has been withdrawn far enough to permit of the discharge of the gate. The rod, or ejector, 44 may be actuated in any suitable manner but in the present instance it is controlled by a hand operated lever 45 pivotally mounted at one end, as shown at 46, and having its other end arranged at that side of the machine adjacent to the operator's station where it can be readily manipulated by him. To control the movement of the ejector rod I have arranged the lever between stops 47 mounted on a rod 48 extending rearwardly from the rear supporting member 6.

In certain types of castings, such for instance as the type, or counter, wheel, above mentioned, it is necessary that portions of the die be moved outwardly to release the casting before the latter can be ejected. In the particular die here shown, see Fig. 5, the type faces are formed in radial bars 49 which form the peripheral portion of the die opening and in order that these radial bars may be withdrawn to permit the removal of the casting each is provided with a pin 50 which extends into a cam groove 51 formed in a ring, or actuating member, 52, rotatably mounted in the die block 8. The arrangement is such that when the actuating member, or ring, 52 is rotated for a partial revolution the walls of the cam groove will act on the pins 50 and impart radial movement to the bars of the die, or to the

other parts which must be moved to release the casting. I prefer that this movement should be imparted to the actuating member 52 automatically and to that end I have provided the actuating member, or ring, with an operating arm, or lever, 53 which is rigidly secured thereto and extends upwardly from the die block. This lever is connected with a cable 54, one portion of which extends about a guide pulley 55 mounted on the upper edge of the rear die supporting member 6 and is rigidly secured to the forward die supporting member 5. That portion of the cable 54 on the other side of the lever 53 extends about a guide pulley 57 on the rear die supporting member and has connected therewith a weight 58. It will be apparent, therefore, that as the two die supporting members are separated movement may be imparted to the cable 54 and consequently to the lever 53 which is secured to the actuating device. Upon the next operation of the machine and as the rear die supporting member approaches the forward die supporting member, the weight 58 will actuate the lever 53 in the opposite direction, thus restoring the movable die parts to their normal positions.

With certain kinds of castings it is desirable that the rearward movement of the die supporting member should be interrupted, before the ejectors are actuated, to permit of the removal of a core or other part necessary to the forming of the casting and which must be removed before the casting is ejected. I have, therefore, provided means for automatically interrupting the operation of the hydraulic mechanism and providing the desired dwell in the movement of the die supporting member. To accomplish this I have provided means controlled by the movement of the die supporting member to automatically move the controlling valve for the cylinder into its neutral position.

In the present construction I have connected with the handle 32 of the valve, and preferably with a disk 59 by means of which the handle is secured to the shaft 30, a connecting rod 60, the lower end of which is pivotally connected with an arm 61 pivotally mounted on a bracket 62 and having a nose, or trigger, 63 which extends into the path of a projection, or stop, 64 mounted on the piston rod 13. The stop 64 is mounted on the piston rod in such a position that it will engage the trigger 63 and cause the valve to be moved into its neutral position when the rear die supporting member has reached the desired position, and when it is not necessary to interrupt the movement of the die supporting member this stop may be moved into an inoperative position or entirely removed from the piston rod. After the core has been removed or the other desired operation performed, the valve

is manually actuated to again admit fluid in front of the piston 12 and cause the movement of the die supporting members to be completed. Inasmuch as the projection 64 will remain in engagement with the trigger 63 it would be impossible to again restore the valve to its operative position and I have, therefore, provided means for automatically imparting a slight further movement to the piston, after the valve has been moved to its neutral position, which movement will be sufficient to carry the projection 64 beyond the trigger, thereby releasing the latter and permitting the valve to be actuated. To accomplish this I have mounted on the frame of the machine an air cylinder 65, the lower end of which is interposed in the pipe 20 which connects the valve with the front end of the cylinder 11. Consequently, the fluid, or oil, passing through the pipe 20 to the cylinder will enter the cylinder and compress the air in the upper portion thereof and when the valve has been closed this air will expand, thus ejecting the oil from the cylinder 65 to the cylinder 11, thereby imparting a slight forward movement to the piston.

In the operation of the ordinary die casting machine a great many defective castings result from blow holes due to the entrance of air into the die along with the metal. The molten metal is admitted to the pressure chamber, or goose neck, at relatively long intervals and after a number of castings have been made it will fall to such a low level that the air which is utilized for forcing the metal into the die will escape in small quantities about the metal in the goose neck and enter the dies. Further, as the level of the metal in the chamber, or goose neck, falls a thin deposit of metal is left on the sides of the chamber and in a comparatively short time this deposit builds up to such an extent as to so interfere with the operation of the device that it is necessary to discard the melting pot. In the present device I have provided a melting pot which not only adequately prevents the entrance of air into the dies along with the metal but also reduces to a minimum the deposit of metal on the walls of the pressure chamber, thereby greatly lengthening the life of the melting pot. This I accomplish by maintaining the pressure chamber substantially full of molten metal at all times during the operation of the machine, a quantity of metal being delivered to the pressure chamber upon each operation of the machine to compensate for the metal discharged from the pressure chamber to make the casting. In the present construction the melting pot is indicated as a whole by the reference numeral 66 and comprises a main compartment, or receptacle, 67, in which the metal is melted, and a pressure

chamber, or goose neck, 68 which receives the metal from the melting compartment and delivers the same to the dies. This pressure chamber is connected at one end with 5 an air pipe, or conduit, 69 leading to a source of supply for air under pressure and controlled by a valve 70. At its opposite end it is provided with a nozzle 71 adapted to enter the tapered opening 43 in the forward die supporting member 5. In the present construction of the melting pot the walls of the melting compartment 67 taper downwardly and the pressure chamber extends from the top of the pot beneath the lowest 10 point thereof and then upwardly a short distance so that the discharge opening or nozzle is arranged in a horizontal plane a short distance above the bottom of the melting compartment. The pot as a whole may 15 be mounted in any suitable manner, but preferably that end thereof adjacent to the discharge nozzle 71 is seated in an opening in the frame member 2 and the other end of the pot is supported by standards 72 20 resting upon the bottom of a casing 73 which encloses the melting pot and within which are arranged the burners for heating the same, these burners not being here shown. The melting compartment is provided 25 at its lowest point with an outlet or port, 74 by means of which the molten metal may flow therefrom into the goose neck, or pressure chamber, 68 and this opening is controlled by a valve 75, which is normally 30 seated in the tapered upper portion of the opening and has an upwardly extending portion, or stem, 76, projecting above the pot and preferably guided in an opening in a bar 77 extending across the top of the 35 pot. I also prefer to provide the valve 75 with a fluted guide 78 which extends into the port 74 and serves not only to guide the valve accurately to its seat but also tends to prevent the pressure in the pressure 40 chamber from forcing the metal from the latter about the valve. The valve stem 76 is pivotally connected at its upper end to a lever 79 which is pivotally mounted at one end on a bracket 80 carried by the adjacent end of the bar 77 and is acted upon 45 at its opposite end by a spring 81 which tends to lift the lever and unseat the valve 75. As here shown, the end of the lever 79 extends between two bars 82 which project 50 upwardly from the horizontal bar 77 and the spring 81 is connected at one end with the lever and at the other end with a projection 83 extending laterally from the bars 82. The lever 79 is held normally in 55 its depressed position, to hold the valve closed, by means of a bar 84 extending between the upper edge of the lever and a stop, here shown as a roller, 85, mounted between the two arms 86 of a bracket which 60 is secured to the bar 77 and extends up- 65 wardly beyond the lever 79. The lever is preferably provided with a roller 87 to facilitate the movement of the bar 84 across the same. The bar 84 is in the nature of a cam bar and has a recess 88 which, when 70 brought into line with the stop 85, will permit the bar, and consequently the lever 79, to move upwardly under the influence of the spring 81, thereby opening the valve. The controlling bar 84 may be actuated in 75 any suitable manner but in order that the operation of the valve may be automatic I have connected this bar with the forward die supporting member 5, by means of a pivot pin 89 and have so arranged the recess 88 that it will be moved past the stop 85 upon each movement of the supporting member 5 in either direction, thus causing the valve to be opened and closed twice upon each complete operation of the mechanism, that is, upon the making of each casting. The length of the recess 88 is such 80 that the valve will remain open for a very short period of time and the upward movement of the valve may be regulated by 85 means of a screw 90 mounted in the upper end of the bracket, or bar, 82 and arranged to regulate the upward movement of the lever. In this manner the amount of metal delivered from the melting compartment to 90 the pressure chamber each time the valve is opened may be accurately regulated, and where, as in the present instance, the valve opens twice upon each operation of the mechanism, the opening of the valve is so 95 regulated and so timed that the amount of metal delivered to the pressure chamber upon each opening of the valve is equal to approximately half the amount of metal discharged from the pressure chamber in 100 the making of the casting. Consequently, the molten metal in the pressure chamber is replenished after each discharge therefrom to maintain the same substantially at 105 a predetermined level, which level is preferably approximately the plane of the lower edge of the discharge opening in the nozzle 71. It will be apparent, therefore, that the whole body of metal in the pressure chamber lies between the air which is admitted 110 to the pressure chamber and the discharge opening and that this air can not escape about the metal to the discharge opening. The small amount of air which may lie 115 in the discharge opening when air is admitted to the pressure chamber will escape to the dies in advance of the metal and will escape through the usual vents with which the dies are provided. As a result, the castings are practically free from blow holes, the 120 percentage of rejections being but a small fraction of one per cent in actual production. The valve 70 which controls the admission of the air under pressure to the pressure chamber may be actuated in any suitable 125 130

manner but as here shown it is actuated by a cable 91 extending about suitable guides and having a depending portion provided with a handle 92 arranged adjacent to the 5 operator's station.

The construction and operation of the mechanism will be readily understood from the foregoing description and it will be apparent that I have provided a die casting 10 machine which can be easily controlled by a single operator. The operations necessary are, first, to open the valve 22 to admit the fluid in the rear of the piston 12, thereby closing the dies and establishing the 15 connection between the same and the melting pot. When this has been accomplished, the valve 70 is opened to admit air under pressure to the pressure chamber of the melting pot, thus forcing the molten metal 20 into the dies and forming the casting. At this time, and preferably before the valve 70 closes, the cutter bar 44 is actuated to cut the gate from the casting. The valve 22 is then reversed and when the die supporting member has moved a sufficient distance from the nozzle 71 the cutter rod 25 is further actuated to eject the gate. If the casting is a simple one with no core to be removed the rearward movement continues until the ejectors 37 are actuated 30 to release the casting, which may be permitted to drop into a suitable receptacle or may be received in the hand of the operator. The casting operation has then been 35 completed and the valve is again opened and the cycle of operations repeated. Not only is it possible for the machine to be thus operated by a single operator but its operation is so easy and so rapid that a 40 single operator can, without exertion, produce a number of castings per hour greatly in excess of what can be produced by any other die casting machine with which I am familiar. Further, because of the freedom from blow holes, there is a very small 45 percentage of rejections and the net production exceeds the net production of such other die casting machines to an extent considerably greater than the gross production 50 of the present machine exceeds the gross production of such other machines. The machine is simple in its construction and is easily maintained in operation, as the parts are not of a delicate or finely adjusted character and are not easily disarranged so as to affect the operation of the machine. Further, little or no adjustment is required in the changing of dies, even 55 through the dies may differ in size and character to a very great extent. This is due to the fluid operated mechanism for actuating the die blocks which permits the die supporting members to automatically adjust themselves according to the size of 60 the die blocks. In the ordinary die cast-

ing machine the die supporting members are moved by means of toggles which must be straightened in order to lock the die supporting members in position. Consequently, if the dies differ in thickness these 70 toggles must be very carefully adjusted to cause the dies to be completely closed and locked.

While I have shown and described one embodiment of my invention I wish it to 75 be understood that I do not desire to be limited to the details thereof as various modifications may occur to a person skilled in the art.

Having now fully described my invention 80 what I claim as new and desire to secure by Letters Patent, is:

1. In a machine of the character described, a melting pot having a discharge opening, means for forcing molten metal 85 through said opening, a die supporting member movable in a right line toward and from said opening, a second die supporting member movable in a right line toward and from the first mentioned member, and a 90 single device for moving said second die supporting member into operative relation with the first mentioned die supporting member and then moving both members to bring the first member into operative relation with said discharge opening.

2. In a machine of the character described, a melting pot having a discharge opening, means for forcing molten metal 100 through said opening, a die supporting member movable in a right line toward and from said opening, a second die supporting member movable in a right line toward and from the first mentioned member, a power operated mechanism a single operation of 105 which will move the second die supporting member into operative relation with the first die supporting member and then move both members to bring the first mentioned member into operative relation with the 110 said discharge opening.

3. In a machine of the character described, a frame having a guideway, a melting pot having a discharge opening arranged near one end of said guideway, 115 means for forcing metal through said discharge opening, a die supporting member slidably mounted on said guideway and movable toward and from said opening, a second die supporting member slidably 120 mounted on said guideway for movement toward and from the first mentioned member, a single operating device having operative connection with said second die supporting member and so arranged that the movement thereof in one direction will move said second die supporting member into operative relation with the first mentioned die supporting member and will then move both members to bring 125 130

the first mentioned die supporting member into operative relation with said discharge opening.

4. In a machine of the character described, a frame having a guideway, a melting pot having a discharge opening arranged near one end of said guideway, means to force molten metal through said discharge opening, a die supporting member slidably mounted on said guideway and movable toward and from said opening, a second die supporting member slidably mounted on said guideway for movement toward and from the first mentioned member, means for maintaining said members in true parallelism, and a single device for moving said second die supporting member into operative relation with the first die supporting member, and then moving both members to move the first mentioned member into operative relation with said discharge opening.

5. In a machine of the character described, a frame having parallel guide rods, a melting pot having a discharge opening arranged near one end of the said frame, means to force molten metal through said discharge opening, sleeves slidably mounted on the respective guide rods, a die supporting member rigidly supported on said sleeves, other sleeves slidably mounted on the first mentioned sleeves, a second die supporting member rigidly secured to the last mentioned sleeves, and an operating device connected with said last mentioned sleeves to move the second die supporting member into operative relation with the first mentioned die supporting member and then move both die supporting members to bring the first mentioned member into operative relation with said discharge opening.

6. In a machine of the character described, a frame comprising parallel guide rods, a melting pot having a discharge opening and means to force molten metal through said discharge opening, a die supporting member having elongated bearings slidably mounted on the respective guide rods, a second die supporting member having elongated bearings slidably mounted on the bearings of the first mentioned die supporting member, and a single operating device for moving said die supporting members relatively one to the other and in unison.

7. In a machine of the character described, a frame comprising parallel guide rods, a melting pot having a discharge opening and means to force molten metal through said discharge opening, a die supporting member having elongated bearings slidably mounted on the respective guide rods, stops on said guide rods to limit the movement of said die supporting member in one direction, a second die supporting mem-

ber having elongated bearings slidably mounted on the bearings of the first mentioned die supporting member, stops carried by the bearings of said first mentioned die supporting member to limit the movement of the last mentioned die supporting member away from the first mentioned die supporting member, and means for actuating said die supporting members relatively one to the other and in unison.

8. In a machine of the character described, a frame comprising parallel guide rods, a melting pot having a discharge opening, means to force molten metal through said discharge opening, a die supporting member having elongated bearings slidably mounted on the respective guide rods, a second die supporting member having elongated bearings slidably mounted on the bearings of the first mentioned die supporting member, said die supporting members being so arranged that said second member will move said first mentioned member toward said discharge opening, and a fluid operated device operatively connected with said second die supporting member.

9. In a machine of the character described, a frame comprising parallel guide rods, a melting pot having a discharge opening and means to force molten metal through said discharge opening, a die supporting member having elongated bearings slidably mounted on the respective guide rods, a second die supporting member having elongated bearings slidably mounted on the bearings of the first mentioned die supporting member, and a fluid operated device operatively connected with said second die supporting member for moving both of said die supporting members to their operative positions and for retracting said second die supporting member, and means other than said fluid operated device for retracting the first mentioned die supporting member.

10. In a machine of the character described, a melting pot having a discharge opening, means for forcing metal through said discharge opening, a die supporting member movable toward and from said discharge opening, a second die supporting member movable toward and from the first mentioned member, a fluid operated device operatively connected with said second die supporting member to move the same toward the first mentioned member and then move both members toward said discharge opening, and a valve controlling the operation of said fluid operated device.

11. In a machine of the character described, a melting pot having a discharge opening, means to force metal through said discharge opening, a die supporting member movable toward and from said discharge opening, a second die supporting member movable toward and from the first

- mentioned member and adapted to move said first mentioned member toward said discharge opening, a hydraulic cylinder, a piston mounted in said cylinder and operatively connected with said second die supporting member, and means for controlling the operation of said piston.
12. In a machine of the character described, a melting pot having a discharge opening, means to force metal through said discharge opening, a die supporting member movable toward and from said discharge opening, a second die supporting member movable toward and from the first mentioned member and adapted to move the said first mentioned member toward said discharge opening, a cross head connected with said second die supporting member, a hydraulic cylinder, a piston for said cylinder, a piston rod connecting said piston directly with said cross head, and means for controlling the movement of said piston.
13. In a machine of the character described, a frame having parallel guideways, a melting pot having a discharge opening, means to force metal through said discharge opening, a die supporting member mounted on said guideways for movement toward and from said discharge opening, a second die supporting member mounted on said guideways and movable toward and from the first mentioned die supporting member, a fluid operated device comprising a cylinder mounted on said frame, a piston for said cylinder, a piston rod for said piston, an operative connection between said piston rod and said second die supporting member, and means for controlling the movement of said piston.
14. In a machine of the character described, a frame having parallel guideways, a melting pot having a discharge opening, means to force metal through said discharge opening, a die supporting member mounted on said guideways for movement toward and from said discharge opening, a second die supporting member mounted on said guideways and movable toward and from the first mentioned die supporting member, a fluid operated device comprising a cylinder mounted on said frame in a line parallel with said guideways, a piston for said cylinder, a piston rod for said piston, an operative connection between said piston rod and said second die supporting means, and means for controlling the movement of said piston.
15. In a machine of the character described, a frame having parallel guide rods, a melting pot having a discharge opening, means to force molten metal through said discharge opening, a die supporting member having elongated bearings mounted on said guide rods and movable toward and from said discharge opening, a second die supporting member having bearings mounted on the bearings of the first mentioned die supporting member and movable toward and from the first mentioned die supporting member, a cross head connected with the bearings of said second die supporting member, a cylinder mounted on said frame on a line parallel with said guide rods, a piston for said cylinder, a piston rod for said piston connected directly with said cross head, and means for controlling the flow of fluid to said cylinder.
16. In a machine of the character described, a frame having parallel guide rods, a melting pot having a discharge opening, means to force molten metal through said discharge opening, a die supporting member having elongated bearings mounted on said guide rods and movable toward and from said discharge opening, a second die supporting member having bearings mounted on the bearings of the first mentioned die supporting member and movable toward and from the first mentioned die supporting member, a cross head connected with the bearings of said second die supporting member, a cylinder mounted on said frame on a line parallel with said guide rods, a piston for said cylinder, a piston rod for said piston connected directly with said cross head, and means for admitting fluid under pressure to either end of said cylinder, and retracting devices connected with the first mentioned die supporting member.
17. In a machine of the character described, a frame, a melting pot carried by said frame and having a discharge opening, means for forcing molten metal through said discharge opening, a die supporting member mounted on said frame for movement toward and from said discharge opening, a die carried by said supporting member having an opening to connect said die with the discharge opening of said melting pot, a second die supporting member mounted on said frame for movement toward and from the first mentioned die supporting member, a die carried by said second member to cooperate with the first mentioned die, means for actuating said die supporting members, a rod mounted in said second die supporting member and extending into the die to form a core therefor, and means for actuating said rod to sever the casting in said die from the metal in the opening leading to the die and for ejecting said metal from said opening.
18. In a machine of the character described, a frame having parallel guides, a melting pot having a discharge opening, means for forcing molten metal through said discharge opening, a die supporting member mounted on said guides for movement toward and from said discharge opening, a die carried by said die supporting member, said die supporting member hav-

- ing an opening to connect said die with said discharge opening, a second die supporting member mounted on said guides for movement toward and from the first mentioned 5 die supporting member, a die carried by said second die supporting member to cooperate with the first mentioned die, means for actuating said die supporting members, a rod mounted in said second die supporting 10 member movable therewith and arranged to form a core for said dies and to sever the casting in said dies from the metal in the opening leading to said dies, and an actuating device movable with said second die supporting 15 member and operatively connected with said rod.
19. In a machine of the character described, a melting pot having a discharge opening, means for forcing molten metal through said discharge opening, a die supporting member mounted for movement toward and from said discharge opening, a die carried by said die supporting member, a second die supporting member mounted for movement toward and from the first mentioned die supporting member, a die carried by said second die supporting member to cooperate with the first mentioned die, means for actuating said die supporting members, 20 one of said dies comprising a part movable away from the casting to release the latter from the die, and means for automatically actuating said part.
20. In a machine of the character described, a melting pot having a discharge opening, means for forcing molten metal through said discharge opening, a die supporting member mounted for movement toward and from said discharge opening, a die carried by said die supporting member, a second die supporting member mounted for movement toward and from the first mentioned die supporting member, a die carried by said second die supporting member to cooperate with the first mentioned die, means for actuating said die supporting members, one of said dies comprising a part movable away from the casting to release the latter from the die, and means for automatically 25 actuating said part.
21. In a machine of the character described, a melting pot having a discharge opening, means for forcing molten metal through said discharge opening, a die supporting member mounted for movement toward and from said discharge opening, a die carried by said die supporting member, a second die supporting member mounted for movement toward and from the first mentioned die supporting member, a die carried by said second die supporting member to cooperate with the first mentioned die, means for actuating said die supporting members, one of said dies comprising a part movable away from the casting to release the latter from the die, and means controlled 30 by the movement of the second die supporting member away from the first die supporting member to move said part of said die into a position to release the casting.
21. In a machine of the character described, a melting pot having a discharge opening, means for forcing molten metal through said discharge opening, a die supporting member mounted for movement toward and from said discharge opening, a die carried by said die supporting member, a second die supporting member mounted for movement toward and from the first mentioned die supporting member, a die carried by said second die supporting member to cooperate with the first mentioned die, means for actuating said die supporting member, one of said dies comprising a plurality of parts having radial movement to release the casting from the die, an actuating device carried by said die and operatively connected 35 with said radially movable parts, an operating arm connected with said actuating device, and means controlled by the relative movement of the die supporting members for imparting movement to said operating arm.
22. In a machine of the character described, a melting pot having a discharge opening, means for forcing molten metal through said discharge opening, die supporting members adapted to support dies in operative relation with said discharge opening, and cooperating dies carried by said die supporting members, one of said dies comprising a part which is movable to release 40 the casting therefrom, and means for actuating said part.
23. In a machine of the character described, a melting pot having a discharge opening, means for forcing molten metal through said discharge opening, die supporting members adapted to support dies in operative relation with said discharge opening, and cooperating dies carried by said die supporting members, one of said dies comprising a radially movable part the movement of which will release the casting from the die, and means for imparting radial movement to said part.
24. In a machine of the character described, a melting pot having a discharge opening, means for forcing molten metal through said discharge opening, die supporting members adapted to support dies in operative relation with said discharge opening, cooperating dies carried by said die supporting members, one of said dies comprising a radially movable part the movement of which will release the casting from the die, and means for automatically 45 actuating said radially movable part.
25. In a machine of the character described, a frame having guideways, a melting pot having a discharge opening, means for forcing molten metal through said discharge opening, a die supporting member mounted on said guideways for movement toward and from said discharge opening, a die carried by said member, a second die supporting member mounted on said guideways for movement toward and from the first mentioned die supporting member, a die carried by said second member, an ejector carried by said second die supporting member and extending into the die, means for actuating said die supporting members, an actuating plate carried by said second die supporting member for imparting movement to said ejector, springs for holding said plate normally in an inoperative position, and stops 50

carried by said frame and arranged in the path of said plate to cause the ejector to be actuated by the movement of said second die supporting member away from the first 5 mentioned die supporting member.

26. In a machine of the character described, a melting pot having a discharge opening, means for forcing molten metal through said discharge opening, a die supporting member adapted to support a die in communication with said discharge opening, a second die supporting member movable toward and from the first mentioned die supporting member, a fluid operated 10 device comprising a cylinder and a piston, an operative connection between said piston and said second die supporting member, a valve to control the flow of fluid to said cylinder, and means to automatically 15 actuate said valve to interrupt the movement of said piston before it has completed its stroke.

27. in a machine of the character described, a frame, a melting pot having a 25 discharge opening, means for forcing molten metal through said discharge opening, a die supporting member adapted to support a die in communication with said discharge opening, a second die supporting member mounted for movement toward and from the first 30 mentioned die supporting member, a fluid operated device comprising a cylinder, a piston and a piston rod for said piston, an operative connection between said piston rod and said second die supporting member, a valve to control the flow of fluid to said cylinder, an actuating device connected with said valve, and a projection carried by said piston rod, said actuating device for said 40 valve having a part arranged in the path of said projection.

28. In a machine of the character described, a frame, a melting pot having a discharge opening, means for forcing molten 45 metal through said discharge opening, a die supporting member adapted to support a die in communication with said discharge opening, a second die supporting member mounted for movement toward and from the first 50 mentioned die supporting member, a fluid operated device comprising a cylinder, a piston and a piston rod for said piston, an operative connection between said piston rod and said second die supporting member, a 55 valve to control the flow of fluid to said cylinder, an actuating device connected with said valve, a projection carried by said piston rod, said actuating device for said valve having a part arranged in the path of said projection, and means to move said projection beyond said part of said actuating device after said valve has been actuated.

29. In a machine of the character described, a frame, a melting pot having a 60 discharge opening, means for forcing molten 65

metal through said discharge opening, a die supporting member adapted to support a die in communication with said discharge opening, a second die supporting member mounted for movement toward and from the first 70 mentioned die supporting member, a fluid operated device comprising a cylinder, a piston and a piston rod for said piston, an operative connection between said piston rod and said second die supporting member, a 75 controlling valve for said cylinder connected with a supply pipe, pipes leading from said valve to the respective ends of said cylinder, an actuating device for said valve comprising a trigger, a tripping device carried by 80 said piston rod and arranged to engage said trigger to move said valve to a neutral position, an air chamber interposed in the pipe leading from said valve to one end of said cylinder whereby the flow of fluid from said 85 valve to said cylinder will compress the air in said chamber, and said compressed air will expand after said valve has been moved to a neutral position and cause a further movement to be imparted to said piston to 90 carry the tripping device on said piston rod beyond said trigger.

30. In a mechanism of the character described, a melting pot comprising a compartment in which the metal is melted, a 95 chamber communicating with said compartment and having a discharge opening, means to force molten metal through said discharge opening, a valve to control the communication between said melting compartment and said chamber, means for automatically actuating said valve upon each operation of said mechanism, and means for controlling the amount of movement imparted to said valve to regulate the amount of metal 100 delivered to said chamber upon each opening of said valve.

31. In a mechanism of the character described, a melting pot comprising a compartment in which the metal is melted, a 110 chamber communicating with said compartment and having a discharge opening, die supporting members one of which is movable, means for discharging molten metal from said chamber to the dies carried by 115 said die supporting members, a valve to control the communication between the melting compartment and said chamber, and means controlled by the movement of said movable die supporting member to actuate 120 said valve.

32. In a mechanism of the character described, a melting pot comprising a compartment in which the metal is melted, a chamber communicating with said compartment and having a discharge opening, a die supporting member movable toward and from said discharge opening, a second die supporting member movable toward and from the first mentioned die supporting 125 130

member, means for discharging molten metal from said chamber to the dies carried by said die supporting members, a valve to control the communication between said melting compartment and said chamber, and means controlled by the movement of one of said die supporting members to actuate said valve.

33. In a mechanism of the character described, a melting pot comprising a compartment in which the metal is melted, a chamber communicating with said compartment and having a discharge opening, a die supporting member movable toward and from said discharge opening, a second die supporting member movable toward and from the first mentioned die supporting member, means for discharging molten metal from said chamber to the dies carried by said die supporting members, a valve to control the communication between said melting compartment and said chamber, a lever operatively connected with said valve, and means controlled by the movement of one of said die supporting members to actuate said lever.

34. In a mechanism of the character described, a melting pot comprising a compartment in which the metal is melted, a chamber communicating with said compartment and having a discharge opening, a die supporting member movable toward and from said discharge opening, a second die supporting member movable toward and from the first mentioned die supporting member, means for discharging molten metal from said chamber to the dies carried by said die supporting members, a valve to control the communication between said melting compartment and said chamber, a lever operatively connected with said valve, means controlled by the movement of one of said die supporting members to actuate said lever, and adjustable means to regulate the amount of movement imparted to said lever.

35. In a mechanism of the character described, a melting pot comprising a compartment in which the metal is melted, a chamber communicating with said compartment and having a discharge opening, a die supporting member movable toward and from said discharge opening, a second die supporting member movable toward and from the first mentioned die supporting member, means for discharging molten metal from said chamber to the dies carried by said die supporting members, a valve to control the communication between said melting compartment and said chamber, a lever operatively connected with said valve, an actuating bar connected with one of said die supporting members and extending between said lever and a fixed stop and having a cam surface to cause said lever to be

operated by the movement of said die supporting member.

36. In a mechanism of the character described, a melting pot comprising a compartment in which the metal is melted, a chamber communicating with said compartment and having a discharge opening, a die supporting member movable toward and from said discharge opening, a second die supporting member movable toward and from the first mentioned die supporting member, means for discharging molten metal from said chamber to the dies carried by said die supporting members, a valve to control the communication between said melting compartment and said chamber, a lever operatively connected with said valve, a spring acting on said lever to move the same in a direction to open said valve, a bar connected with one of said die supporting members and extending across said lever, and a fixed stop arranged to normally prevent the movement of said bar and said lever and having a recess adapted to be brought into line with said stop by the movement of said die supporting member and thus permit said lever to be actuated by said spring.

37. In a mechanism of the character described, a melting pot comprising a compartment in which the metal is melted, a chamber communicating with said compartment and having a discharge opening, a die supporting member movable toward and from said discharge opening, a second die supporting member movable toward and from the first mentioned die supporting member, means for discharging molten metal from said chamber to the dies carried by said die supporting members, a valve to control the communication between said melting compartment and said chamber, a lever operatively connected with said valve, a spring acting on said lever to move the same in a direction to open said valve, a bar connected with one of said die supporting members and extending across said lever, a fixed stop arranged to normally prevent the movement of said bar and said lever and having a recess adapted to be brought into line with said stop by the movement of said die supporting member and thus permit said lever to be actuated by said spring, said recess being so arranged that it will be twice moved into and out of line with said stop upon each complete reciprocation of said die supporting member.

38. In a mechanism of the character described, a melting pot comprising a compartment in which the metal is melted, a chamber communicating with said compartment and having a discharge opening, a die supporting member movable toward and from said discharge opening, a second die supporting member movable toward and from

the first mentioned die supporting member, means for discharging molten metal from said chamber to the dies carried by said die supporting members, a valve to control the communication between said melting compartment and said chamber, a lever operatively connected with said valve, a spring acting on said lever to move the same in a direction to open said valve, a controlling bar pivotally mounted on one of said die supporting members and having its lower edge resting upon said lever, a bracket

extending above said lever and having a stop to engage the upper edge of said bar, said bar having a recess in its upper edge 15 adapted to be brought into and out of line with said stop by the movement of said die supporting member, thereby causing the valve to be opened and closed upon each movement of said die supporting member. 20

In testimony whereof, I affix my signature hereto.

GEORGE W. SMITH.
